[57] CLAIM

The ornamental design for a coffee brewer support stand, as shown and described.

DESCRIPTION

FIG. 1 is a front elevational view of a coffee brewer support stand showing my new design; the broken line showing of a coffee brewer is illustrative of environmental structure only and forms no part of the claimed design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and

FIG. 7 is a perspective view thereof.

FIG. 1

FIG. 2

FIG. 3

FIG. 4

FIG. 5

FIG. 6

FIG. 7
